UNITED STATES PATENT OFFICE.

FRANK W. MILLIKEN, OF AUBURN, MAINE, ASSIGNOR OF ONE-HALF TO CHENEY C. BROWN, OF AUBURN, MAINE.

AUTOMATIC SPRINKLER ALARM AND INDICATOR SYSTEM.

1,153,400.

Specification of Letters Patent. Patented Sept. 14, 1915.

Application filed February 2, 1915. Serial No. 5,777.

To all whom it may concern:

Be it known that I, FRANK W. MILLIKEN, citizen of the United States, residing at Auburn, in the county of Androscoggin and 5 State of Maine, have invented certain new and useful Improvements in Automatic Sprinkler Alarm and Indicator Systems, of which the following is a specification.

This invention relates to improvements 10 in automatic sprinkler alarm and indicator systems, and particularly to certain changes in and additions to the apparatus shown in my Patent, No. 977,391, but it is not thereby intended to limit the invention, except 15 as expressed in the claims to the apparatus described in my said patent.

One object of the present invention is to provide means for giving an alarm whenever the supply from the main to the system is for any reason cut off, so that it will 20 be impossible for any person to shut the supply from the system without proper warning.

Another object is to provide the apparatus 25 with a double alarm, each working independently of the other, one being electrically controlled and the other mechanically.

Another object is to provide an apparatus 30 which works automatically under all conditions.

Another is to provide means to keep the signaling apparatus from operating while the system is being charged, and then maintaining it open and in ready condition.

35 In the drawing herewith accompanying and making a part of this application the figure is a detail elevation, partly in section, showing so much of a sprinkler system and of my improvements as is necessary 40 to illustrate its construction and explain its operation.

In said drawing A is a main supply pipe, B a portion of the sprinkler system service pipe and B' a sprinkler head. The service 45 pipe is provided with an alarm valve comprising a casing C having a port D therein adapted to be normally closed by a gravity valve E. This port leads through a pipe F, into chamber G and discharges into an open 50 receptacle H set on a pivoted bar I, said receptacle being counterbalanced by a weight J. The receptacle has an opening K in the bottom which is of less diameter than that of the pipe F, allowing the receptacle to fill

to give the alarm and then to empty automatically when the inflow ceases. In pipe F is a shut-off valve A' which is to be shut when the system is being charged and then locked open. Attached to the receptacle is a rack arm L which works in engagement 55 with pinions M which carry movable contact points M' which when the receptacle descends are made to complete a circuit through the contact N and battery O, and thereby ring the bell P and move the indicator Q. These parts are substantially the same and operate substantially in the same manner as in my said patent.

Between the alarm valve casing C, before described, and the main, I insert a shut-off 70 valve consisting of a valve casing R having an extension S in the bottom, and mounted in said valve casing R is a wedge shaped valve T on the lower end of which is a rod U carrying a valve V adapted to close an 75 opening V' in the bottom of the casing, the extension S permitting the valve V to pass away from its seat, which occurs whenever the valve T begins to descend to close the passage from the main to the sprinkler service pipe. When this occurs the water from the main flows through the pipe F to the receptacle H, which becoming overbalanced 80 descends in the chamber making the electrical contact, ringing the bell and operating 85 the indicator, giving notice that the supply is shut off from the main.

To provide an auxiliary alarm which will work positively and mechanically and to supplement the electrical alarm, I provide 90 at some convenient point in the receptacle chamber a valve casing W in which is a valve X operated by a valve stem Y attached to the arm of the rod which supports the receptacle H. Leading from the service pipe 95 B to the valve casing W is a pipe Z the end of which is closed by the valve X. Now, whenever the receptacle H is overbalanced it opens the valve X and allows the water 100 to flow through pipe W' and into a motor Z', conventionally shown, which may be connected to and adapted to operate an alarm apparatus not shown.

The advantages of my system are that the main supply cannot be shut off and the system emptied without giving notice, and the 105 certainty of the notice is assured by the auxiliary alarm apparatus, the water motor

giving the alarm, even if the electric current is broken and inoperative. It will be evident that any liquid may be used.

Having described my invention and its use I claim:

- 5 1. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a shut-off valve casing in the main, a pipe leading from said casing to the receptacle, a double valve in said casing, one adapted to close the main pipe and the other to close the pipe leading to the receptacle, said valves being arranged so that the latter opens as the former starts to close the main.
- 10 2. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a shut-off valve in the main pipe and means controlled thereby for operating the make and break means to operate the alarm whenever the water is shut off from the main.
- 15 3. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.
- 20 4. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.
- 25 5. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.
- 30 6. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.
- 35 7. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.
- 40 8. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.

balanced receptacle, an open conduit leading from said branch pipe to said receptacle, and adapted to be normally closed by said valve when seated and to discharge into said receptacle when said valve is open, an electric circuit, an alarm mechanism, means operable by movement of said receptacle to make and break said circuit and operate said alarm, a shut-off valve casing in the main, a pipe leading from said casing to the receptacle, a double valve in said casing, one adapted to close the main pipe and the other to close the pipe leading to the receptacle, said valves being arranged so that the latter opens as the former starts to close the main.

45 9. In an automatic sprinkler alarm and indicator system, a water main, a branch pipe leading therefrom, a valve seat and valve located in said branch pipe, a counterbalanced receptacle, an open conduit leading from said branch pipe to said receptacle and adapted to be normally closed by said valve when seated and to discharge into said receptacle when said valve is open, an electric circuit, an alarm mechanism, means operable by movement of said receptacle to make and break said circuit and operate said alarm, a water motor, a pipe leading from the sprinkler system to said water motor, a valve located in said latter pipe adapted to be opened by the fall of said receptacle, thereby allowing the water to flow into and operate said motor, and an auxiliary alarm operated by said motor.

50 10. In testimony whereof I affix my signature in presence of two witnesses.

FRANK W. MILLIKEN.
